TRIMMER FOR BATTERY SEPARATORS

Filed Jan. 13, 1930

UNITED STATES PATENT OFFICE

LAWRENCE P. ERPELDING, OF INDIANAPOLIS, INDIANA

TRIMMER FOR BATTERY SEPARATORS

Application filed January 13, 1930. Serial No. 420,535.

This invention relates to a trimming machine for thin sheets such as veneer and the like, particularly such as storage battery insulation separators.

5 The chief object of the invention is to provide a device which has a relatively large capacity and which will readily and without breakage to the articles to be operated upon or to the machine, trim and/or size a 10 group of sheet material, such as battery separators.

One feature of the invention consists in the sheet clamping construction and the association therewith of a traveling carriage preferably in the continued movement of a member initially actuated for clamping of the sheets.

Another feature of the invention consists 20 in the oscillating pair of spaced knives between which the carriage and supported sheets pass for trimming and for sizing to a predetermined width determined by the spacing of the knives.

A third feature of the invention consists 25 in the guide and the adjustable mounting thereof whereby the sheets to be trimmed are readily positioned upon the clamping carriage in substantially parallel and aligned relation whereby a minimum of trimming 30 will be required and therefore the rough stock sheets may be of a minimum initial size.

A fourth feature of the invention consists 35 in the offset connection of the knives to the crank shaft for power balancing.

The full nature of the invention will be understood from the accompanying drawings and the following description and claims.

In the drawings Fig. 1 is a side elevation 40 of a machine embodying the invention. Fig. 2 is a top plan view thereof. Fig. 3 is a central sectional view of the clamping carriage and the support therefor. Fig. 4 is a transverse sectional view of the same taken on line 4-4 of Fig. 3 and in the direction of the 45 arrows.

In the drawings 10 indicates the bed of a machine provided with the usual legs or end frames 11. Any suitable support however, may be provided. A motor 12 through a belt 50 13 or equivalent device, drives a pulley 14

carried by shaft 15. Shaft 15 includes a pair of crank portions 16 offset 180 degrees.

Extending from the platform or base 10 is a pair of upstanding arms 17 each of which pivotally supports as at 18 a link 19. Link 55 19 is pivotally connected at 20 to the upper end of the vertically arranged connecting rod 21 supporting the cutting blade 22. The lower end of said connecting rod is supported by the crank portion as at 23. The knives are 60 maintained in substantially parallel relation and in predetermined spaced relation and are oscillated simultaneously but one knife is in advance of the other by 180 degrees which serves to balance the machine and secures 65 greater uniformity in cutting. The crank portions 23 are diametrically offset for power balancing.

At the end of the machine opposite from the motor 12 and to one side there is mounted a locating or guide plate 30 and the same carries a pair of pins 31 which project through and are slidably supported by a rigid frame member of plate 33, the latter having holes 34 provided for such purpose. Coil 70 springs 35 retained by washers 36 normally constrain the clamping plate toward the retracted position, that is they tend to position plate 30 adjacent plate 33. Each of the four corners of the plate 30 supports the inner end 75 of a screw construction 40. Each screw passes through plate 33 and terminates in the exposed sprocket 41. The sprockets 41 are all connected together by a chain construction 42 and one of the screw shafts 43 mounts a 80 handle 44 whereby all of the screw shafts are simultaneously turned in the same direction to simultaneously advance and retract all 85 four corners of the plate 30 so that plate 30 will always lie parallel to plate 33 and in 90 the adjusted position. The usual threaded connection associated with the several shafts 43 is provided to obtain such operation.

Extending longitudinally and medianly of 95 the machine and depending from the carriage, is a pair of spaced angle members 50 which provide a T-slot therebetween and form a slide way for the carriage 52 and members 50 are carried thereby. The base 10 centrally supports an I-member 51 with a 100

T-shaped head, having a central longitudinal groove 51a therein—see Fig. 4. Carriage 52 has a transverse flange 53 that supports a front plate 54. A back plate 55 is carried by the back support 56 secured to the groove located plate 58a secured together as at 59a. The two plates 54 and 55 have relative movement toward and away from each other as shown. A lever 57 having one end 58 socketed at 58b in plate 58a is pivotally supported at 59 on the arm 60 rigid with plate 54. Extending upwardly from the arm 60 is a handle 61 and the lever 57 terminates in a handle 62 positioned adjacent handle 61.

15 The position of plate 30 is adjusted through the handle 44. The carriage is retracted so as to be positioned forwardly of the knives and the two plates 54 and 55 are separated by the tilting of the lever handle 62 away from plate 54. The sheets of veneer, separators or the like are then positioned between the two plates 54 and 55 and are crowded laterally against plate 30 as a guide. When the space between the two plates 54 and 55 is substantially filled handle 62 is moved toward handle 61 and the two handles are gripped together. The initial lever movement causes clamping of the two plates against the sheets. Continued application of pressure serves to push 30 the carriage toward the motor and in so doing the carriage with the two plates and the sheets passes between the two knives.

Each sheet has a predetermined width and two parallel sides. To prevent chipping of the knife blades by engagement with the plates, each plate is provided at each corner with a vertical insert of soft metal such as lead and the same is indicated at 70 in Figs. 2 and 3. Upon completing the trimming of 40 all sheets the carriage is retracted, the lever 62 released and the trimmed sheets removed and replaced by untrimmed sheets. The trim or waste falls to the floor or may be collected in suitable containers beneath the platform.

45 Suitable guides or direction plates 80 are secured to frame adjacent the knives so that the trimmings are directed outwardly from the knives and carriage whereby the same have free travel.

50 The invention claimed is:

1. In a trimming machine the combination with a carriage, a slideway supporting the same, a handle for sliding the carriage thereon, and a pair of clamping plates carried by the carriage, of a lever for adjusting the plate spacing and including a handle positioned adjacent the first mentioned handle whereby upon initial application of power, the plates cause a clamping action and upon completing 60 same continued power application secures carriage sliding movement.

2. In a trimming machine, the combination with a carriage, a slideway supporting the same, a pair of spaced oscillatable knives, 65 said carriage being movable therebetween, a

handle for sliding the carriage on said slideway, and a pair of clamping plates carried by the carriage for holding a plurality of sheets in substantially parallel and rigid relation upon said carriage, with a lever for adjusting the plate spacing and including a handle positioned adjacent the first mentioned handle whereby upon initial application of power, the plates cause a clamping action and upon completing same continued power application secures carriage sliding movement.

3. In a trimming machine, the combination with a reciprocating carriage, a slideway supporting the same, and a guide plate positioned adjacent thereto and parallel to the carriage movement, of a handle for sliding the carriage on the slideway, a pair of clamping plates carried by the carriage and angular of said guide plate, a lever for adjusting the clamping plate spacing and including a handle positioned adjacent first mentioned handle whereby upon initial application of power the plates cause a clamping action and upon completing the same continued power application secures carriage sliding movement, a pair of oscillatable knives said carriage being movable therebetween, said sheet clamping plates having a width dimension substantially that of the knife spacing for full sheet support, and means associated with said clamping plates providing relatively softer edges thereon for knife edge protection.

4. In a sheet guide and trimmer the combination with a travelling carriage, sheet clamping means carried thereby, a guide plate parallel to the carriage for sheet edge engagement and alignment, and a pair of cutters movable to and fro in parallel planes, 105 of means eccentrically mounting the cutters relative to each other for simultaneously, moving said cutters in power balancing relation.

In witness whereof I have hereunto affixed 110 my signature.

LAWRENCE P. ERPELDING.
